UNITED STATES PATENT OFFICE.

GEORGE D. WATSON, OF TORRANCE, CALIFORNIA, ASSIGNEE TO UNION TOOL COMPANY, OF TORRANCE, CALIFORNIA, A CORPORATION OF CALIFORNIA.

ROTARY STRAIGHT-HOLE BIT.

Application filed May 17, 1924. Serial No. 714,016.

To all whom it may concern:

Be it known that I, GEORGE D. WATSON, a citizen of the United States, residing at Torrance, in the county of Los Angeles and State of California, have invented a new and useful Rotary Straight-Hole Bit, of which the following is a specification.

This invention relates to drilling bits of the type used in drilling deep wells such as 10 oil wells.

In drilling with fish-tail bits, where the cutting end of the drill is encountering hard material which is not of sufficient extent to be engaged by the entire lower end of the bit 15 there is a tendency for the hard material to cause the bit to lean over or become inclined in the earth. This is objectionable and may produce an irregular or crooked hole. In drilling with ordinary fish-tail bits it also 20 happens that they may twist off due to the fact that the cross section of the metal on the blade of the bit is not sufficiently large. Furthermore, the water holes in a fish-tail bit deliver the water on each side and in a 25 direction to strike the side of the hole; this tends to scour off the sides of the hole and is objectionable.

The general object of this invention is to produce a bit which will overcome these defects and which will operate to drill a straight hole by utilizing the bore produced by the bit as a guide; also to produce a bit which will have an increased area of cross section and with the metal distributed so as 35 to resist the high torsional strains which are developed in the bit in cutting.

A further object of the invention is to provide special means on a bit of this type for insuring the delivery of the drilling 40 water to the cutting point in such a way as to prevent its scouring the side of the hole.

Further objects of the invention will appear hereinafter.

The invention consists in the novel parts 45 and combination of parts to be described hereinafter, all of which contribute to produce an efficient rotary straight hole bit.

In the drawings:

Figure 1 is a front elevation of a bit embodying my invention.

Figure 2 is a side elevation of the bit shown in Fig. 1.

Figure 3 is a vertical section through the bit projected on the same plane as in Fig. 2.

Figure 4 is an end view of the bit.

Figure 5 is a perspective, broken away, and illustrating the preferred form of the lower end of the bit, on reduced scale.

The bit constructed in accordance with my invention is provided with means such 60 as a tapered pin 1 for securing it to the lower end of the tool string. The body 2 of the bit has a substantially "flat" face 3 which lies about in the diametral plane which coincides with the vertical axis of the 65 bit, and coincident with the vertical axis of the pin 1. This face 3, however, is preferably not exactly in the diametral plane but is slightly to one side of the same, see Figure 70 3, in which the line 4 indicates the position 70 of the diametral plane of the tool. The "flat" face 3 of the tool is preferably of substantially rectangular form, that is to say, the side edges 5 of this face are substantially 75 parallel with the axis of the tool.

The lower end of the tool is formed with a cutting point 6 which may be of any desired shape. The body of the tool presents a smooth convex rear face 7 which is preferably of cylindrical form, so that the cross 80 section of the body of the tool is substantially semi-circular or what is known popularly as "half-round" form.

The upper end of the body 2 is formed 85 into a bolster or boss 8 which may be substantially circular across section. On the forward side of the tool this boss extends down so that it projects well down and over the upper portion of the substantially flat face 3 of the bit. The radius of this boss 90 8 is, of course, considerably less than the distance from the axis of the bit to the convex face 7, so that a semi-annular shoulder 9 is formed at the upper end of the bit and around its rear side.

In order to supply water to the cutting point 6 of the tool during rotation, I provide a water duct 10 which passes down along the axis of the bit and pin 1, and the lower end of this water duct emerges 100 at an orifice 11 at the upper portion of the face 3, from which the water is directed vertically downward, and not in an inclined direction as it usually is in a fish-tail bit. In order to facilitate the delivery of water 105 to the cutting point 6 I provide the face 3 with a groove 12 which extends down from the orifice 11 and which operates as a vertical continuation of the water duct 10. As viewed on the forward face 3, this groove 110

tapers in a downward direction and terminates at a point 13 sufficiently near the cutting point 6 to insure delivery of water to it. The side edges 5 of the tool may be 5 dressed or shaped for cutting as may be desired, or if desired the bit may be dressed and finished in the manner of a diamond point bit for drilling out cement.

At its lower portion the boss 8 presents a 10 curved shoulder 14 which operates to guide the muck and dirt up past the projecting portion of the boss which overhangs the flat face 3.

The lower end of the bit at the cutting 15 point 6 is flared, that is to say, as viewed from the front as in Fig. 1, the point 6 projects slightly laterally, and downwardly, and curves forwardly with respect to the direction of rotation of the bit indicated by the 20 arrow in Fig. 1. The preferred shape of the lower end of the bit is illustrated in Fig. 4. The side of the tool is cut away opposite the cutting point by forming a deep notch 6^b extending laterally from the central axis of 25 the tool.

It will be evident that as rotation of the bit takes place, the radius to the point 6^a, (see Fig. 4) will determine the diameter of the hole which is being produced by the bit, 30 and as the bit moves down through the earth the hole formed will provide clearance for the body of the bit, which will maintain the convex face 7 against the side of the hole; in this way the hole operates to guide 35 the bit as it advances. In other words, the bore of the well cooperating with the convex or cylindrical face 7, operates to prevent any tilting or "cocking" of the bit as it advances, and likewise will prevent "cocking" 40 of the bit if it should twist off.

In using the term "flat" to describe the face 3 of the bit, I mean simply that the face is a depressed face and is relatively flat; in other words this face is produced by 45 cutting away the body of the tool on one side.

It is understood that the embodiment of the invention described herein is only one of the many embodiments this invention 50 may take and I do not wish to be limited in the practice of my invention, nor in my claims, to the particular embodiment set forth.

I claim:

55 1. A rotary straight hole bit having an elongated body with a pin at its upper end for securing it to the lower end of the tool-string, said body having a depressed side face lying near the diametral plane passing 60 through the vertical axis of the bit and having a cutting point at its lower end operating during the rotation of the tool to determine the diameter of the bore formed by the tool, said bit having a smooth convex rear 65 face which maintains contact with the side

of the bore and is guided by the bore as the bit advances.

2. A rotary straight hole bit having an elongated body with a pin at its upper end for securing it to the lower end of the tool-string, said body having a depressed side face lying near the diametral plane passing through the vertical axis of the bit, and having a flared cutting point at its lower end operating during the rotation of the tool to 70 determine the diameter of the bore formed by the tool, said bit having a convex rear face which maintains contact with the side face of the bore and is guided by the bore as the bit advances, the upper end of said bit having a substantially circular boss carrying said pin and extending at its lower end down and over the said flat face.

3. A rotary straight hole bit having an elongated body with a pin at its upper end for securing it to the lower end of the tool-string, said body having a substantially flat depressed side face lying near the diametral plane passing through the vertical axis of the bit, and having a cutting point at its 80 lower end, said bit having a smooth convex rear face which maintains contact with the side of the bore formed by the bit and guided by the bore as the bit advances, said pin having a water duct passing substantially 85 vertically through the same and emerging from the bit on the said substantially flat face.

4. A rotary straight hole bit having an elongated body with a pin at its upper end for securing it to the lower end of the tool-string, said body having a depressed side face lying near the diametral plane passing through the vertical axis of the bit, and having a flared cutting point at its lower end operating during the rotation of the tool to 100 determine the diameter of the bore formed by the tool, said bit having a convex rear face which maintains contact with the side of the bore and is guided by the bore as the bit advances, and also having a water duct passing substantially 105 vertically down through the pin on the axis thereof, emerging at the upper portion of the said substantially flat face, said depressed face having a groove cut thereon extending downwardly from the point of emergence of the duct.

5. A rotary straight hole bit having an elongated body with a pin at its upper end for securing it to the lower end of the tool-string, said body having a substantially flat face lying near the diametral plane passing through the vertical axis of the bit, and having a flared cutting point at its lower end, said bit having a convex rear face which maintains contact with the side of the bore formed by the bit and guided by the bore as the bit advances, said bit having a 115 boss of substantially circular form carrying 120

the pin and coaxial with the pin, said boss extending down and projecting over the upper portion of the said substantially flat face, said pin and said boss having a water duct passing substantially vertically there-through and emerging at the lower end of the boss and on the said substantially flat face, the said flat face having a groove cut therein extending downwardly from the point of emergence of the duct and operating as a continuation of the water duct to guide the water down along the said flat face to the cutting point.

6. A rotary straight hole bit having an elongated body with means at its upper end

for securing it to the lower end of the tool string, said body having a depressed side face lying near the diametral plane passing through the vertical axis of the bit, and having a cutting point at its lower end operating during the rotation of the tool to determine the diameter of the bore formed by the tool, said bit having a smooth convex rear face which maintains contact with the side of the bore and is guided by the bore as the bit advances.

Signed at Torrance, Calif., this 6th day of May, 1924.

GEORGE D. WATSON.
